(57) **CLAIM**

The ornamental design for a climb and crawl activity playset, as shown and described.

DESCRIPTION

FIG. 1 is a top perspective view of a climb and crawl activity playset, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the first piece of the climb and crawl activity playset of FIG. 1 thereof;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a top perspective view of the second piece of the climb and crawl activity playset of FIG. 1 thereof;

FIG. 17 is a front view thereof;

FIG. 18 is a rear view thereof;

FIG. 19 is a left side view thereof;

FIG. 20 is a right side view thereof;

FIG. 21 is a top view thereof;

FIG. 22 is a bottom view thereof;

FIG. 23 is a top perspective view of the third piece of the climb and crawl activity playset of FIG. 1 thereof;

FIG. 24 is a front view thereof;

FIG. 25 is a rear view thereof;

FIG. 26 is a left side view thereof;

FIG. 27 is a right side view thereof;

FIG. 28 is a top view thereof;

FIG. 29 is a bottom view thereof;

FIG. 30 is a top perspective view of the fourth piece of the climb and crawl activity playset of FIG. 1 thereof;

FIG. 31 is a front view thereof;

FIG. 32 is a rear view thereof;

FIG. 33 is a left side view thereof;

FIG. 34 is a right side view thereof;

FIG. 35 is a top view thereof;

FIG. 36 is a bottom view thereof;

(Continued)

FIG. 37 is a top perspective view of the fifth piece of the climb and crawl activity playset of FIG. 1 thereof;
 FIG. 38 is a front view thereof;
 FIG. 39 is a rear view thereof;
 FIG. 40 is a left side view thereof;
 FIG. 41 is a right side view thereof;
 FIG. 42 is a top view thereof; and,
 FIG. 43 is a bottom view thereof.
 The claim is directed to the collective appearance of the climb and crawl activity playset shown in the figures. The components of the set are arranged on the drawing sheets for the convenience of illustration, and the relative positioning of the climb and crawl activity playset forms no part of the claimed design.

1 Claim, 43 Drawing Sheets
